HOLDER FOR FASTENERS

Eldon L. Krieg, South Whitley, Ind.

Application April 7, 1947, Serial No. 739,847

5 Claims. (Cl. 1—47)

1

My invention relates broadly to a tool for facilitating nailing of fasteners and more particularly to an improved construction of fastener grip for use in nailing.

One of the objects of my invention is to provide a construction of fastener grip which may be readily held in one hand while wielding a hammer with the other hand in performing a nailing operation.

Another object of my invention is to provide a construction of fastener grip in the form of tongs, the jaws of which are normally spring pressed together for gripping a fastener and in which the jaws may be readily spread to receive, guide, grip and/or release a fastener in performing a nailing operation.

Still another object of my invention is to provide an improved construction of fastener grip in which a pair of spring pressed tong-like jaws are spreadable within predetermined limits for receiving, gripping, guiding and/or releasing fasteners such as nails, brads, tacks, etc., in performing a nailing operation.

Still another object of my invention is to provide a construction of tongs for gripping a fastener between a pair of relatively narrow jaws which may be introduced into extremely cramped space in which there is very little clearance for holding the nail, brad, tack or staple in an angular position for performing a nailing operation.

A still further object of my invention is to provide a construction of tool formed by a pair of relatively slender tong-like resiliently tensioned arms, one of which is curved to substantially embrace the other and which terminates in a position forming an abutment for limiting the spreading relation of said tong-like arms.

Still another object of my invention is to provide a construction of fastener grip including a pair of slender operating arms therefor in which said arms are yieldably spring pressed together and one of said arms shaped to provide a supporting hook or extension handle for the device.

Other and further objects of my invention reside in the structural arrangement of fastener grip as set forth more fully in the specification hereinafter following by reference to the accompanying drawings in which:

Figure 1 shows the fastener grip of my invention as it is held in the hand while performing a nailing operation; Fig. 2 is an enlarged plan view of the fastener grip showing the position of the tongs when gripping a nail; Fig. 3 is a side elevational view of the fastener grip illustrated in Fig. 2; Fig. 4 is a plan view of the fastener grip with

2

the arms spread preparatory to gripping a fastener or immediately subsequent to the release of the fastener; Fig. 5 is an enlarged fragmentary side elevational view of the end of the fastener grip with a portion thereof illustrated in longitudinal section substantially on line 5—5 of Fig. 4 and Fig. 6 is a transverse sectional view taken substantially on line 6—6 of Fig. 2.

My invention is directed to an inexpensive and efficient construction of tool formed by a pair of relatively narrow coacting handles crossed adjacent the ends thereof and pivoted to provide a pair of preformed coacting jaws for gripping and holding a fastener such as a nail, brad, tack, etc., with the tool grasped in one hand while wielding a hammer with the other hand for driving the nail, brad, tack, etc. The handles of the tool are formed in a very special manner wherein one of the handles terminates in a position within the curvature of the other of the handles. A curved portion of one handle serves as a limiting stop for a spreading operation of the first mentioned handle. Spring means are provided between the handles for normally maintaining the jaws in a gripping position for gripping a nail, brad, tack, etc., the arms being separable by a spreading operation against the constant tension of a transversely extending spring member disposed within the arms. The curvature of one arm serves as a limiting stop for predetermined the maximum spreading distance for the arms and the associated coacting jaws.

Referring to the drawings in detail reference characters 1 and 2 designate the coacting arms of a tong-like tool which are flattened at 1a and 2a to cross each other at the pivotal position 3 at which they are pivoted by rivet member 4. The arms 1 and 2 cross each other at the pivotal position 3 and terminate in slender jaw-like portions 1b and 2b. The slender jaw-like portions 1b and 2b abut each other in contacting faces 1c and 2c. These abutting faces are shaped to receive the nail or staple to be gripped. A groove corresponding to the shape of the nail or staple to be gripped is provided in each of the abutting coacting faces 1c and 2c. This groove is angularly disposed as represented more clearly in Fig. 5 by reference character 2d. The groove 2d is semi-cylindrical in section and similarly the coacting groove 1d is semi-cylindrical in section so that by the conjoint abutting relation of faces 1c and 2c a fastener is gripped between the abutting faces of the tool in an angular position properly aligned for nailing.

In Fig. 3 I have illustrated the manner in which

the angularly inclined grooves $1d$ and $2d$ in coacting faces $1c$ and $2c$ grip the fastener 5 and maintain the fastener 5 in an angular position. This permits the nailing to be effected in extremely close quarters and within narrow confines. The tool is readily grasped in one hand as represented in Fig. 1 and held at the desired angle for maintaining the desired angular position of the fastener while wielding a hammer with the other hand for driving the fastener.

The coacting arms 1 and 2 of the tool differ in construction as arm 1 is provided with a recess or transverse groove 6 therein and is curved around the end of arm 2 in spaced relation thereto as represented at 7 and terminates in a flattened portion 8 aligned with the end of arm 2 . Arm 2 terminates in a position substantially coincident with the center about which a radius may be drawn substantially conforming with the curvature 7 of arm 1 as represented more particularly at 9 in Fig. 1. The terminus of arm 2 is grooved adjacent the end thereof as represented at 10 . Between the recess or groove 6 and the groove 10 I provide a compression spring 11 which is hooked around recess or groove 6 as represented at 12 and which extends around groove 10 in arm 2 as represented at 14 . Compression spring 11 thus tends to maintain faces $1c$ and $2c$ in intimate engagement for gripping the fastener therebetween. By applying pressure with the fingers as illustrated in Fig. 1 with the tool held in the hand and the extended curved shank 7 resting against the palm of the hand, the faces $1c$ and $2c$ are spread allowing a fastener to be inserted or released.

The faces $1c$ and $2c$ are limited in the distance in which they may be spread by reason of the abutment of the end of arm 2 with the flattened end 8 of the curved portion 7 of arm 1 . Such an abutting position is being approached in the spreading operation as illustrated in Fig. 4. Upon abutment of the end of arm 2 with the abutment face 8 of arm 1 spring 11 is prevented from being further stretched thereby prolonging the life of the spring and preventing damage and injury to the spring tension.

The curvature 7 of arm 1 insures the convenient handling of the device and prevents slippage of the tool during a nailing operation. Moreover, the curved portion 7 of the tool provides a means for hanging or suspending the tool. Such suspension of the tool is extremely convenient, for example, when putting up inside window shade brackets on window frames. An operator standing on a stepladder may hook the curved end 7 of the tool in a shirt or garment pocket when the tool is not in use permitting unrestricted use of the hands. The curvature 7 of the handle 1 also provides a means for hooking the tool over a work bench in a convenient position ready for assisting in a nailing operation at any time.

The shape of the jaws $1b$ and $2b$ and the arrangement of the recesses $1d$ and $2d$ in the faces $1c$ and $2c$ thereof form an important feature of my invention. As represented in Figs. 1, 2 and 4 the terminus of the tool is nose-like formed by the two coacting jaws $1b$ and $2b$. The radius of the nose-like jaws viewed in plan is located at substantially the center of the rear portions abutting faces $1c$ and $2c$ intermediate the recesses $1d$ and $2d$ and the apices of the rear portions of the faces $1c$ and $2c$ as represented in Fig. 5 at $2e$. That is to say, the radius when viewed in plan of the nose-like end of the jaws has a

center substantially at $2f$ whereby the nose-like circular outline for the ends of the jaws is formed on radius 15 . The ends $1g$ and $2g$ of the nose-like terminus are formed on an acute angle with respect to the bottom faces represented at $2h$ to enable the tool to be tilted into a position most convenient for gripping and guiding a slender fastener into driving position. The angularly disposed ends $1g$ and $2g$ are directed on the same angle as the axis of the recesses $1d$ and $2d$. A central opening 16 is provided between the jaws $1b$ and $2b$ intermediate the pivotal position 3 and the abutting coacting faces $1c$ and $2c$. This arrangement permits the efficient gripping of the fastener during the driving operation.

I have found the tool of my invention extremely practical in its manufacture and production and efficient in its use, and while I have described my invention in one of its preferred embodiments I realize that modifications may be made and I intend no limitations upon my invention other than may be imposed by the scope of the appended claims.

What I claim as new and desire to secure by Letters Patent of the United States is as follows:

1. A tool for gripping and guiding a fastener for performing a driving operation, comprising a pair of pivotally mounted arms terminating in coacting jaws, each having recessed abutting coacting faces, said faces operating to grip and support a fastener in driving position, one of said arms terminating in a curved portion extending substantially around the end of the other of said arms and providing an abutment for limiting the movement thereof and spring means extending between said arms for tensioning said arms and normally maintaining said coacting faces in closed coacting relation.

2. A tool for gripping and guiding a fastener for performing a driving operation, comprising a pair of pivotally mounted arms terminating in coacting jaws, each having recessed abutting coacting faces, said faces operating to grip and support a fastener in driving position, one of said arms terminating in a curved portion ex-

tending substantially around the end of the other of said arms and providing an abutment for limiting the movement thereof, said arms each being grooved at transversely opposite positions therein and spring means extending between the transversely grooved positions for tensioning said arms and maintaining said coacting faces in closed position one with respect to the other.

3. A tool for gripping and guiding a fastener for performing a driving operation, comprising a pair of pivotally mounted arms terminating in coacting jaws, each having recessed abutting coacting faces, said faces being grooved along an axis extending substantially at an acute angle to the bottom face of said jaws and having nose portions extending at an acute angle to the bottom face of said jaws in substantially parallel alignment with the axis of said grooves whereby the terminus of said jaws may be fitted into extremely limited spaces, one of said arms substantially surrounding the end of the other of said arms and forming a limiting abutment for restricting the spreading of said arms and spring means extending between said arms for normally maintaining said jaws in gripping relation with respect to the fastener which is to be driven.

4. A tool for gripping and guiding a fastener for performing a driving operation, comprising a pair of pivotally mounted arms terminating in

coacting jaws, each having recessed abutting coacting faces, said faces operating to grip and support a fastener in driving position, one of said arms being formed in a curve with the terminus of the other of said arms as a center for the radius defining the curvature of said first mentioned arm whereby the curved end of said first mentioned arm constitutes an abutment for limiting the movement of the second mentioned arm and correspondingly limiting the spreading of said coacting jaws, and spring means extending between said arms for tensioning said arms and normally maintaining said coacting faces in closed coacting relation.

5. A tool for gripping and guiding a fastener for performing a driving operation, comprising a pair of pivotally mounted arms terminating in coacting jaws, each having recessed abutting coacting faces, said faces operating to grip and

support a fastener in driving position, one of said arms being formed on a curve extending substantially around the end of the other of said arms and terminating in a flattened abutment 5 directed toward said last mentioned arm and providing an abutment for restricting the movement thereof and spring means extending between said arms for tensioning said arms and normally maintaining said coacting faces in closed coacting relation.
